UNITED STATES PATENT OFFICE.

ANNIE E. MORSE, OF MONTREAL, CANADA.

CAP.

SPECIFICATION forming part of Letters Patent No. 690,982, dated January 14, 1902.

Application filed May 29, 1901. Serial No. 62,360. (No model.)

To all whom it may concern:

Be it known that I, ANNIE E. MORSE, of Montreal, Province of Quebec, Canada, have invented certain Improvements in Caps, of which the following description, in connection with the accompanying drawings, is a specification, like figures on the drawings designating like parts.

This invention relates to wearing-apparel, and more particularly to head-coverings, and has for its special object the provision of a cap with a member arranged to prevent disarrangement of the hair upon the forehead of the wearer and also to exclude all dust from the hair.

My improved cap will be found of notable utility as a sleeping-cap for women employing an elaborate coiffure; but I do not limit myself to its utilization for this purpose, contemplating its use in any field to which it may be adapted by reason of its novel construction and arrangement of parts.

The various features of my invention are illustrated and set forth fully in the accompanying drawings and description and pointed out in the claims.

In the drawings, Figure 1 is a view in side elevation of a cap in the construction of which my improvements have been embodied. Fig. 2 is a view in perspective of the same, and Fig. 3 a plan view of a detail to form the subject of more specific description herein-after.

In the form of cap selected for illustration and description as a convenient embodiment of my invention to enable a ready comprehension of the improvements presented thereby the reference-numeral 1 designates the body of the cap, which may be of any desired and suitable material and shape, but preferably will conform to the style of coiffure employed by the wearer and may have strings 2 or other usual or suitable means to secure the cap to the head by tying under the chin, as shown in Fig. 2, or otherwise.

At the portion of the cap-body adjacent the

forehead, as at 3, I provide an auxiliary member 4, which may and preferably will be secured permanently to the body of the cap, a convenient form of joint being illustrated at 50 5, where I have shown a strong and at the same time ornamental union, the material of the member 4 being extended laterally in the form of a point 5, which is secured by suitable means 6, as by stitching, to the body. 55

Upon donning the cap the free ends of the member 4 will be fastened in any suitable manner, a simple method being to tie them in a bow at the nape of the neck, as shown in Fig. 2. The cap thus applied will be secure 60 upon the head, and therefore particularly advantageous for use upon sleeping-caps and in similar situations.

Having thus fully described my invention, the advantages whereof will be readily apparent without further detailed statement, I wish it understood that I do not limit myself to the specific construction illustrated and described, nor in general otherwise than as set forth in the claims, taken in connection 70 with the specification.

What I claim, and that upon which I desire to secure protection, is—

1. As a new article of wearing-apparel, a cap having a body portion to receive the head 75 of the wearer and an auxiliary member adjacent the fore portion of the cap to overlie and protect the hair upon the forehead of the wearer, said member having fastening means on each side of the medial operating portion. 80

2. A cap of the class described having a body portion, and a band connected with the forepeak of the body and having free attaching ends.

In testimony whereof I have signed my 85 name to this specification in the presence of two subscribing witnesses.

ANNIE E. MORSE.
